SOUND AMPLIFYING APPARATUS

Filed March 12, 1924

INVENTOR

Adolph A. Thomas

UNITED STATES PATENT OFFICE

ADOLPH A. THOMAS, OF NEW YORK, N. Y., ASSIGNOR TO RADIO CORPORATION OF AMERICA, OF NEW YORK, N. Y., A CORPORATION OF DELAWARE

SOUND-AMPLIFYING APPARATUS

Application filed March 12, 1924. Serial No. 698,596.

My invention relates generally to loudspeakers and is particularly applicable where the amplifying horn of a phonograph is used as a loudspeaker for a radio set, especially where the phonograph and radio set are in the same cabinet. The object of my invention is to provide a new and improved tone arm to which a telephone receiver may be attached above the top board of the phonograph without removal of the phonograph sound box and independently thereof.

Broadly stated, the basic idea of my invention comprises a phonograph tone arm provided with means for supporting a telephone receiver above the top board of the phonograph in acoustic connection with the tone arm, without removal of the sound box and without interfering with the movements of the sound box and the tone arm when the phonograph is playing. When the telephone receiver is operating, the vibrations thereof are transmitted through the tone arm, independently of the sound box and without removing the latter. Accordingly, when my invention is applied in a combination radio-phonograph cabinet, the phonograph horn constitutes the common sound amplifier for both the phonograph mechanism and the radio set, and the machine is always ready to operate as a phonograph or as a loudspeaking radio set without disconnecting the sound box or removing any other part of the phonograph mechanism. In my new radio-phonograph tone arm, the telephone receiver is acoustically connected to the tone arm by means of a tubular extension on the tone arm, this extension being arranged to receive a telephone receiver without removal of the sound box and without interfering with its movements into and out of playing position.

At the present time I prefer a construction in which the tone arm has a pair of tubular extensions, or a tubular extension comprising a pair of branches. On one of these extensions or branches is mounted a sound box, and the other extension is arranged to receive a telephone receiver without removing the sound box. The two extensions or branches are so constructed and arranged that they conduct the sound waves through the body

of the tone arm. This arrangement is preferably, but not necessarily, carried out by forming the extensions as a tubular fork or Y-connection at the outer end of the tone arm, thus avoiding sharp turns in the sound passage leading from either branch of this connection to the main body of the tone arm. The sound box is permanently mounted on one branch of the fork, and the telephone receiver is connected to the open end of the other branch without removal of the sound box and independently thereof. In fact, the telephone receiver may, if desired, be permanently attached to its branch or tubular extension without interfering with the operation of the sound box. If the telephone receiver is connected to a radio set, the phonograph tone arm and horn may be used as a loudspeaker without the trouble of removing the sound box, as was necessary in prior constructions. By connecting the telephone receiver to the tone arm above the motor board of the phonograph, the receiver is always readily accessible for adjustment, replacement, or any other purpose.

My new tone arm may also be provided with a manually adjustable valve for closing either branch when the other is in use. Such a valve, however, is not necessary where the branches are arranged at such an angle that sound waves pass easily from either branch through the tone arm with practically no interference from the other branch even without a valve, as will be clear later on.

In order to explain my invention, I have shown in the accompanying drawings a construction which I prefer at the present time, it being understood that this is merely an illustrative embodiment. In these drawings—

Fig. 1 is a plan view of a phonograph cabinet embodying my new tone arm, the telephone receiver of a radio set being shown disconnected from the tone arm;

Fig. 2 is a view similar to Fig. 1, with the telephone receiver acoustically connected to the tone arm independently of the sound box and without removal thereof;

Fig. 3 is an enlarged sectional view of the tone arm, showing how the tubular branches

or extensions lead into the body of the tone arm, and also showing a valve for shutting off either branch; and

Fig. 4 is an enlarged detached view on line 5 4-4 of Fig. 1, showing the valve in side elevation.

The cabinet A, of suitable construction and design, contains phonographic reproducing mechanism, of which I need only show the 10 turntable 1, and the tone arm T. The turntable is driven by a motor in the cabinet, as will be understood, and the tone arm is acoustically connected with an amplifying horn, roughly indicated by dotted lines 2, 15 built into the cabinet in the usual way.

The tone arm T, preferably of the tapering type, is swivelled at its base 4 on the motor board 3, so as to swing horizontally, as is usual in phonographs. The outer end of 20 tone arm T terminates in a forked or Y-shaped connection comprising a pair of tubular branches 5 and 6. On branch 5 is swivelled a curved tube 7 (commonly called a goose-neck) carrying a sound box or 25 producer 8 of any suitable construction.

Fig. 1 shows the sound box in playing position, and in Fig. 2 the sound box is thrown back, resting against a stop 9 on the tone arm.

The outer end of the tubular branch or 30 extension 6 is normally closed by a cap 10, which may be held in place in any suitable way, as by friction or screw-threads, or otherwise. The branch 6 is adapted to receive a telephone receiver R for amplifying the sound 35 vibrations thereof through the tone arm and horn of the phonograph. We may suppose, for illustration, that the telephone receiver R is connected to a radio set in the cabinet by means of wires 11 passing through a hole 12 40 in the motor board 3. It will not be necessary to show or describe any structural details of receiver R, because there are many kinds of such receivers in the market. To 45 connect the telephone receiver R to the tone arm T, it is only necessary to remove cap 10 from branch 6 and slip the receiver on to the outer open end of this branch tube. That is all there is to it; no removal of the sound box, and no mutilation or damaging of any part 50 of the phonograph. In fact, the telephone receiver may be left permanently attached to branch tube 6 without interfering with the operation of the sound box or with the horizontal movements of the tone arm across the 55 record. It will be noticed that the weight of the telephone receiver is not communicated to the sound box. The phonograph is, therefore, always in playing condition. When in the claims I speak of the sound box being 60 permanently attached to the tone arm, I do not mean that the sound box is not removable from the arm, as for repair or replacement, but I simply mean that it need not be taken off in connecting and operating the telephone 65 receiver.

As seen from Fig. 3, the branches 5 and 6 are preferably so arranged that they form unbroken continuations of the main body of the tone arm, being only slightly curved with respect thereto. Differently stated, the extension tube 6 for the telephone receiver preferably projects at an acute angle to the longitudinal axis of the tone arm, so that the junction of these two parts is formed without a sudden angular turning, which might interfere with the proper passage of sound. As a result, sound waves coming through either branch issue easily (that is, without undue break) into the body of the tone arm, with no appreciable loss or interference on account of the uncovered inner opening of the other branch. The forked or V-shaped extension 5-6 may be formed integral with the main body of the tone arm, or it may be cast separately and attached to the tone arm in any 85 practical way.

If desired, a suitable valve may be provided to close the inner end of either branch tube when the other is in use. For this purpose, I have shown a valve 13 in the form of a properly shaped vane fixed on a pivot 14 mounted at the junction point of the branch tubes. A finger piece or handle 15, preferably pointing in the same direction as valve 13, is attached to or formed on rod 14, to throw the valve into either closing position. For instance, in Fig. 3, valve 13 is shown in full-lined position to close the inner end of branch 5, and in dotted lines 13' to close the branch 6. The shape of valve 13 is such that it forms a tight closure in either position and remains firmly in adjusted position by friction or otherwise. Valve 13 may consist of a metal plate edged with rubber, leather, or the like. The precise structure of this valve is immaterial, as long as it properly fulfills its function. The operator can always tell the position of the valve by the position of finger piece 15, since the two are always in alignment. Thus, in Fig. 1, finger piece 15 shows that branch 6 is closed at the inner end, and in Fig. 2 the position of finger piece 15 indicates that branch 5 is closed. That part 15 thus performs the double function of an operating lever for the valve 13 and a visual indicator for the position of the valve. As previously stated, valve 13 is not necessary in the broader aspect of my invention, although it may be employed to advantage.

Nor is it necessary that the radio set of telephone receiver R be mounted in cabinet A, as in combined radio and phonograph cabinets, although this arrangement is preferable on account of its compactness. In that case, the telephone receiver R forms part of the regular cabinet equipment and, when not in use, may rest on the motor board, as shown in Fig. 1, or it may be left attached to the branch 6 without interfering with the phonograph as such.

It will be seen from the foregoing that I have provided simple means for attaching a telephone receiver to a phonograph tone arm independently of the sound box and without removal thereof. I do not herein claim this idea broadly, because that is covered in my copending application, Serial Number 639,240, filed May 16, 1923, as a division of my prior application Serial Number 562,278, filed May 20, 1922. The present case, excepting valve 13, contains matter in my aforesaid pending applications and is a continuation in part thereof.

Although I have herein shown and described a specific construction of tone arm, I want it understood that I have done so merely to explain my invention by means of an illustrative embodiment, and not by way of restriction or limitation. Manifestly, the fundamental idea of my invention may be mechanically carried out in various other forms without departing from the scope of the invention as defined in the appended claims.

25 I claim as my invention:

1. In a phonograph having a top board, a tone arm extending above said board and having a sound box permanently mounted thereon, a rigid branch tube projecting laterally 30 from said tone arm at an acute angle to the longitudinal axis of said arm, so that sound waves pass easily from said branch tube into the tone arm, said branch tube being arranged entirely above said board, and a telephone 35 receiver adapted to be connected to the free end of said branch tube without removal of the sound box and without interfering with the movements of the sound box into and out of operative position.

40 2. In a phonograph having a top board, a tone arm extending above said board and terminating at its outer end in a rigid forked extension consisting of a pair of branch tubes. a sound box permanently mounted on one of 45 said branch tubes, both of said branch tubes being arranged entirely above said board, and a telephone receiver adapted to be mounted on the other branch tube for acoustic connection with the tone arm independently of the sound box and without removal thereof.

3. A phonograph tone arm terminating at its outer end in a pair of branch tubes, a sound box permanently mounted on one of said tubes, a telephone receiver mounted on the other tube for acoustic connection with the tone arm independently of the sound box and without removal thereof, a swinging vane mounted at the junction point of said branch tubes and extending toward the main body of the tone arm for closing the inner end of either tube, and a finger piece for operating said vane and simultaneously indicating its position.

4. A phonograph tone arm terminating at 65 its outer end in a pair of branch tubes, a

sound box permanently mounted on one of said tubes, a telephone receiver mounted on the other tube for acoustic connection with the tone arm independently of the sound box and without removal thereof, a swinging vane mounted at the junction point of said branch tubes and extending toward the main body of the tone arm for closing the inner end of either tube, and a hand lever connected to the axis of said vane for operating the same, 70 said lever extending in fixed alignment with the vane for visually indicating the position thereof.

5. In a phonograph having a top board, a tone arm pivotally mounted over said board 80 and provided with a sound box, and a rigid tubular extension at or near the outer end of the tone arm for receiving a telephone receiver to connect the same acoustically with the tone arm without removal of the sound box, said extension terminating above said board and being so arranged that the telephone receiver mounted thereon does not interfere with the proper operation of the sound box and the swinging movements of 90 the tone arm.

6. In a phonograph having a top board, a tone arm having a sound box permanently mounted thereon, a rigid branch tube projecting laterally from said tone arm at such 95 an angle to the longitudinal axis of said arm that sound waves pass easily from said branch tube into the tone arm, said branch tube being arranged entirely above said board, and a telephone receiver supported on the free 100 end of said branch tube without interfering with the phonographic operation of the sound box.

7. In a phonograph having a top board, a horizontally swinging tone arm provided with a swivelled sound box, a rigid tube projecting from said tone arm in such a direction that sound waves pass easily from the tube into the tone arm, said tube terminating above said board, and a telephone receiver supported on the free end of said tube without interfering with the movements of the tone arm and the sound box.
